UNITED STATES PATENT OFFICE.

TRUE J. SMITH, OF TOPEKA, KANSAS.

FENCE-POST.

SPECIFICATION forming part of Letters Patent No. 296,237, dated April 1, 1884.

Application filed January 10, 1884. (No model.)

To all whom it may concern:

Be it known that I, TRUE J. SMITH, a citizen of the United States, and a resident of Topeka, in the county of Shawnee and State of Kansas, have invented certain new and useful improvements in Fence-Posts; and I do hereby declare that the following is a full, clear, and exact description of the invention, which will enable others skilled in the art to which it applies to make and use the same, reference being had to the accompanying drawings, which form a part of this specification, and in which—

Figure 1 is a perspective view of my improved fence-post. Fig. 2 is a longitudinal sectional view of the same, and Fig. 3 is a cross-section through line $x-x$ in Fig. 2.

Similar letters of reference indicate corresponding parts in all the figures.

My invention has relation to metallic fence-posts; and it consists in the improved construction of a post of that class, which will be hereinafter more fully described and claimed.

In the accompanying drawings, A is a piece of bar-iron, of suitable dimensions, which is doubled upon itself so as to form a loop or eye, B, at the upper end. One of the doubled parts or legs A' of the post is then twisted at right angles, as shown at C, and brought up against the other flat part or leg, A, to which it is connected by pieces of wire D, the free ends of which are twisted around the fence-wires E, as shown at F, to form tyers or binders for the same. Thus it will be seen that these twisted wires D F serve the double purpose of connecting the two parts or pieces A and A' and of fastening the fence-wires to the post, the binders being inserted through holes G bored or punched through the part A'. The lower end of the leg A is twisted at right angles at H, so as to be in a plane with the leg C' of part A', and these two legs C' and H are

connected by a cross-brace, I, which also serves the purpose of anchoring the post firmly in the ground.

In using the post it may be inserted into the ground up to the point where the legs C' and H diverge, or the diverging point may be where the bottom fence-wire, E, is fastened to the post. The uppermost binding-wire is inserted through the loop B in the top of the post, and twisted around the uppermost fence-wire on opposite sides, as shown in the drawings.

I am aware that metallic fence-posts have been heretofore constructed consisting of a single piece of suitable metal bent at right angles upon itself, having its lower diverging ends connected by a suitable brace and provided with wire ties, which serve the double purpose of connecting the two parts of the post together and of fastening the fence-wires to the post, and I do not therefore claim such construction, broadly; but

What I claim as my invention, and desire to secure by Letters Patent of the United States, is—

The metallic fence-post herein shown and described, consisting of the parts A and A', doubled upon and at right angles to each other, and bent or twisted to form the flat loop B at the top of the post, and the diverging legs C' and H, curved so as to lie in the same plane with one another, and connected by a cross-brace, I, in combination with the twisted binding-wires D F and the fence-wires E, as shown and specified.

In testimony that I claim the foregoing as my own I have hereunto affixed my signature in presence of two witnesses.

TRUE J. SMITH.
